United States Patent Office

Des. 212,751

Patented Nov. 19, 1968

212,751

REVOLVER

William B. Ruger, Southport, Conn. 06490

Continuation-in-part of design application Ser. No. 2,589, June 7, 1966. This application May 8, 1967, Ser. No. 8,197

Term of patent 7 years

(Cl. D22—1)

FIG. 9

FIG. 8

FIG. 7

FIG. 1 is a perspective view of a revolver showing my new design;

FIG. 2 is a rear end elevational view of the revolver of FIG. 1;

FIG. 3 is a front end elevational view of the revolver of FIG. 1;

FIG. 4 is a top plan view of the revolver of FIG. 1;

FIG. 5 is a side elevational view of the revolver of FIG. 1, the opposite side being the same, with a portion of the broken line structure omitted for convenience of illustration;

FIG. 6 is an under plan view of the revolver of FIG. 1;

FIG. 7 is a perspective view of the modified form of a revolver showing my new design;

FIG. 8 is a rear end elevational view of the revolver of FIG. 7;

FIG. 9 is a front end elevational view of the revolver of FIG. 7;

FIG. 10 is a top plan view of the revolver of FIG. 7;

FIG. 11 is a side elevational view of the revolver of FIG. 7 with a portion of the broken line structure omitted for convenience of illustration;

FIG. 12 is an under plan view of the revolver of FIG. 7; and

FIG. 13 is a side elevational view of the revolver of FIG. 7 showing the side opposite to that in FIG. 11.

The essential features of the design reside in the rear portion shown in full lines.

This application is a continuation-in-part application of Ser. No. D.2,589, filed June 7, 1966, and now abandoned.

I claim:

The ornamental design for a revolver, as shown and described.
